UNITED STATES PATENT OFFICE.

JOSEPH J. PERCIVALL, OF EAST ORANGE, NEW JERSEY.

RUBBER HEEL.

Application filed June 13, 1922. Serial No. 568,024.

To all whom it may concern:

Be it known that I, JOSEPH J. PERCIVALL, a citizen of the United States, and resident of East Orange, in the county of Essex and State of New Jersey, have invented certain new and useful Improvements in Rubber Heels, of which the following is a specification.

My present invention relates to improvements in rubber heels whereby I am able to provide ample cushioning spaces therein without sacrificing the bodily integrity and strength of the heel. The result is that the heel is an excellent shock-absorber and supports the weight without breaking down even after long use. These and other objects and advantages will appear from the following description and drawings.

In the accompanying drawings, Fig. 1 is a top plan view of a rubber heel of my invention which embodies my improvements in their preferred form, the dotted lines indicating the outline of invisible portions or parts within the body of the heel; Fig. 2 is a vertical cross sectional view on the line 2—2 in Fig. 1 looking in the direction of the arrows; and Fig. 3 is also a vertical cross sectional view on the line 3—3 in Fig. 1 looking in the direction of the arrows.

Describing now the aforesaid preferred embodiment of my invention, 1 is the rubber or equivalent resilient body of the heel, 1^a being its top surface to be applied next the shoe and 1^b being its ground or tread surface.

2 is a relatively large central space in the body of the heel located wholly above the tread and opening upwardly through the top of the heel, said space having undercut, preferably substantially concave side-walls 2^a.

3—3 are a plurality of elongated cushioning spaces within the heel body bordering the space 2 and located between it and the sides of the heel. These spaces 3 are located wholly above the tread and open through the top of the heel by means of narrow slots 3^a. They also have undercut preferably concave side-walls 3^b. In the form shown, the spaces 3 are substantially cylindrical in transverse section.

4—4 are vertical nail holes through the heel from top to bottom. These are part of the means for attaching the heel to the shoe; and are spaced around the periphery

of the heel alternating with the spaces 3, between the ends of which they are located.

Each nail hole 4 has an enlarged conical part 4^a at the tread leading to a cylindrical passage 4^b having about the diameter of the head of one of the attaching nails; said passage 4^b in turn leading to a cylindrical passage 4^c of much smaller diameter to fit the shank or stem of the nail. 4^c is a metal washer molded in the body of the heel between the passages 4^b and 4^d and having a hole through it of the same diameter as said passage 4^d and continuous therewith. As shown, there is one of these washers for each nail hole.

In attaching the heel, the nails are entered pointwise into the mouths 4^a and 4^b of the holes and thence through the holes in the washers and into 4^c. Then by using a suitable follow-up tool, the nails are driven into the heel of the shoe until their heads lodge against the washers 4^c.

The construction of the heel is such that it is adapted to be molded as a unit, the cylindrical cores for molding the spaces 3 being pulled through the slots 3^a.

The drawings show how the undercutting of the walls of the spaces 2 and 3 enables them to be brought closely together as well as closely to the sides of the heel, without unduly weakening the intervening and adjacent weight-supporting rubber walls. The result is that the heel has high shock-absorbing value without sacrificing its ability to stand up even after long use.

My heel accomplishes this and yet is unusually light. Thus, I prefer to make the central opening 2 extra large which materially lightens the heel,—relying on the border portion to do the main work of supporting the weight. The spaces 3 cushion this border portion assisted by the space 2, which latter, of course, also cushions shocks coming from the tread of the heel immediately under said space 2.

Finally, it is important to note that the undercutting of the walls of the spaces 2 and 3 provides ample sized cushioning spaces without sacrificing the tops of the walls which are left intact and provide an amply large area for firmly cementing the rubber heel to the heel of the shoe in the usual way before the nails are driven into the holes 4.

It is possible that changes and modifications may be made in the illustrative em-

bodiment of my invention which will nevertheless still be within the scope and spirit of my invention and within the scope and spirit of the annexed claim, and as such 5 are intended to be covered thereby. Also certain features may be used without others.

What I claim is:

A rubber heel having formed therein a

plurality of elongated upwardly opening recesses bordering the periphery of the heel 10 with undercut, substantially concave side-walls.

Signed at New York, in the county of New York and State of New York this 12th day of June, A. D. 1922.

JOSEPH J. PERCIVALL.
